EX

OR D 11,742

100. DESIGN

Organ Cases.

No. 11.742.

Apr. 20. 1880.

UNITED STATES PATENT OFFICE.

ALBERT WAGNER, OF NEW YORK, N. Y., ASSIGNOR TO J. ESTEY & CO., OF
BRATTLEBOROUGH, VT.

DESIGN FOR AN ORGAN-CASE.

SPECIFICATION forming part of Design No. 11,742, dated April 20, 1880.

Application filed February 3, 1880. Term of patent 14 years.

To all whom it may concern:

Be it known that I, ALBERT WAGNER, of the city, county, and State of New York, have invented or produced a new and original Design for Organ-Cases, (style 330,) which I have 5 assigned to J. Estey & Co., and of which the following is a specification.

My improved case relates to what are known as "chapel-organ cases," the back being finished as well as the front; and in its general features it resembles the case patented to J. Estey & Co., May 8, 1877, by Design Patent No. 9,958, differing from that, however, in that the back is nearly flat, instead of being shaped 15 in imitation of the front.

In the accompanying photographic illustrations, Figure 1 is a perspective view of the front of an organ-case made after my design; and Fig. 2 is a similar view of the rear of the 20 same.

Let A A designate the ends of the case, and B the intervening body, of which latter C is the front board, and D the back board. The ends A A project considerably above the body 25 B, and are surmounted by flower-stands a a, while below a horizontal bar-handle, b, extends across from stile to stile. The body B of the case extends between the ends in a series of straight lines. Generally speaking, these features are shown in the patent hereinbefore referred to.

I provide each end A with a cornice or molding, d, upon which I superimpose a top piece, e, of thinner material than the end below the 35 cornice, and I form the top piece with a small upward projection at front and rear, and with a higher central projection, which bears the flower-stand a.

E is the console or key-board bracket, arranged against and extending forward from the end A, and made solid opposite the end of the key-board, as usual, and somewhat open below, being there composed of a vertical prismatic front bar, f, rectangular in cross-section, 45 and insulated by openings g and h from a rear bar, i, which is planted against the front stile of the end A. Opposite the top of the bar f a roll, j, depends from the solid portion of the bracket. The base-board of the end A is 50 shown as continued out under the bracket E. k is a lamp-stand, supported on a bracket, l.

The front board, C, is divided into three panels, which are embellished by a series of parallel stripes, each formed of close parallel lines, and by a series of equal-sided figures, as shown, 55 interposed equidistantly between some of the stripes.

F is the front of the key-board projection, which is embellished by one or more elongated openings containing a design which consists of a series of diversified X-shaped figures, as shown, crossing the opening at equal distances apart.

G is the lid, which is crossed longitudinally by parallel linear strips, as shown. 65

On top of the body B of the case, and between its elevated ends A A, I place a rectangular music-rack, m, flanked by strips c c, which extend to the ends A A. The rack m and strips c c are set edgewise in the same 70 vertical plane, and are arranged in a plane intermediate of the front and back of the case. The music-rack projects considerably higher than the strips, is provided with end stiles 75 surmounted by knobs, and has a serrated or inverted upper edge. It is also ornamented by a row of perforations flanked by parallel lines or stripes. The strips c c, which answer to the similarly-placed strip in Design Patent No. 9,958, before referred to, are shown as 80 provided with closely-arranged vertical openings.

The back board, D, is divided by a transom and mullions into a horizontal opening or recessed panel, H, above, and vertical panels I I 85 below. The transom and mullions are ornamented with longitudinal stripes p p of parallel lines.

The panel or opening H is embellished with a series of rectangular outlines vertically arranged, and a quadrangular figure placed cornerwise within each. I contemplate substituting an open-work panel for the opening H, the rectangular outlines being openings, and the quadrangular figures being solid ornaments inserted within the openings. I also 95 contemplate bringing the open-work panel and its surrounding frame out in advance of the remainder of the back board, D.

The center panel I is embellished with two 100 parallel stripes of lines and dots, and in its center with a rosette arranged within a recti-

linear outline. The side panels I I are each ornamented with a diagonal stripe, which consists of a row of small circular figures flanked by parallel lines, and from each side of the 5 stripe branches a spiral line or similar figure.

J J are vertical bars or posts, which cover the rear faces of the ends A A and extend from about on a level with the top of the body B down to the floor, passing over or across the 10 base-board.

Having thus described my new design, I claim the following as its novel features:

1. The design for an organ-case, consisting of the elevated end A, having a cornice or molding, d, and surmounted by a top piece, e, substantially as shown in the accompanying photographs.

2. The design for an organ-case, consisting of the top piece, e, of thinner material than the 20 end A, superimposed thereupon and bearing the flower-stand a, substantially as shown in the accompanying photographs.

3. The design for the key-board bracket E of an organ-case, consisting of the upright bars f and i, insulated from each other by 25 openings g and h, substantially as shown in Fig. 1 of the accompanying photographs.

4. The design for the key-board bracket E of an organ-case, consisting of the straight 30 prismatic bar f, partially insulated by openings from the parts behind it, and the roll j, depending in front of it from the solid portion of the bracket, substantially as shown in Fig. 1 of the accompanying photographs.

5. The design for the front board, C, of an 35 organ-case, which consists of a series of parallel stripes with intervening spaces, each of said stripes consisting of a series of close parallel lines, substantially as shown in Fig. 1 of the accompanying photographs.

6. The design for the front board, C, of an 40 organ-case, which consists of three panels crossed vertically and horizontally with equidistant parallel stripes of close-lines, substantially as shown in Fig. 1 of the accompanying photographs.

7. The design for the outer panels of the front board, C, of an organ-case, which consists of vertical stripes, with a series of intervening 45 unequal-sided figures equidistantly arranged, substantially as shown in Fig. 1 of the accompanying photographs.

8. The design for the front F of the key-board projection of an organ-case, consisting 50 of an elongated horizontal panel crossed at regular intervals by a series of outlines of substantially X shape, as shown in Fig. 1 of the accompanying photographs.

9. The design for the lid of an organ-case, 55 consisting of parallel stripes arranged longitudinally upon its surface, substantially as shown in Fig. 1 of the accompanying photographs.

10. The design for an organ-case, consisting 60 of the body B, the ends A A, extending above the same, and the music-rack m, arranged upon the body b ween the ends and flanked

by the strips c c, extending to the ends, substantially as shown in the accompanying photographs.

11. The design for an organ-case, consisting of the body B, having a finished front and a finished back, the elevated ends A A, projecting prominently above the top of the body, and the music-rack m, arranged upon the top 75 of the body midway between the elevated ends and in a plane intermediate of the front and back of the body, substantially as shown in the accompanying photographs.

12. The design for an organ-case, consisting 80 of the rectangular music-rack m, flanked by the strips c c, extending to the elevated ends A A, substantially as shown in the accompanying photographs.

13. The design for an organ-case, consisting 85 of the elevated ends A A, with the music-rack m arranged between them, said music-rack being provided with end stiles flanked by the strips c c, extending to the elevated ends, and having a horizontal bar, n, arranged in front 90 of it, substantially as shown in Fig. 1 of the accompanying photographs.

14. The design for an organ-case, consisting of the elevated music-rack m, having a row of perforations, and flanked by the strips c c, having 95 each a row of vertical openings, substantially as shown in the accompanying photographs.

15. The design for an organ-case, consisting of the elevated music-rack m, having a serrated or inverted upper edge, and a row of perforations flanked by parallel lines, substantially as shown in the accompanying photographs.

16. The design for the opening or panel H on the back of an organ-case, consisting of a 105 row of vertical rectangular outlines, with quadrangular figures arranged cornerwise within them, substantially as shown in Fig. 2 of the accompanying photographs.

17. The design for the back of an organ-case, consisting of the back board, D, divided by a transom and mullions into a horizontal panel or opening, H, and vertical panels I I, the said transom and mullions being ornamented with longitudinal stripes p p, substantially as shown in Fig. 2 of the accompanying photographs.

18. The design for the back of an organ-case, consisting of the back board, D, divided into three panels, the center one of which is 120 embellished by a central rosette inclosed by a quadrilateral outline, substantially as shown in Fig. 2 of the accompanying photographs.

19. The design for the back board, D, of an organ-case, consisting of a center panel and 125 two side panels, each of the latter crossed by a diagonal stripe of ornamental linear design, substantially as shown in Fig. 2 of the accompanying photographs.

20. The design for the back of an organ-case, consisting of the side panels I I of the back board, D, crossed diagonally by stripes of ornamental linear design, and the central panel I, crossed by horizontal stripes, sub-

stantially as shown in Fig. 2 of the accompanying photographs.

21. The design for the back of an organ-case, consisting of the side panels I I, crossed by diagonal stripes of ornamental linear design, in combination with the central panel I, bearing a rosette, substantially as shown in Fig. 2 of the accompanying photographs.

22. The design for the back of an organ-case, consisting of the side panels I I, each crossed by a diagonal stripe, consisting of a row of circular figures flanked by parallel lines with spirals branching therefrom, substantially as shown in Fig. 2 of the accompanying photographs.

23. The design for an organ-case, which consists of the vertical posts or bars J J, planted upon the rear face of the ends A A, and extending across the base-board down to the floor, substantially as shown in Fig. 2 of the accompanying photographs.

In witness whereof I have hereunto signed my name in the presence of two subscribing witnesses.

ALBERT WAGNER.
